UNITED STATES PATENT OFFICE

2,245,247

VARIABLE CAPACITY RESERVOIR

Thomas C. Aitchison, Pittsfield, Mass., assignor
to General Electric Company, a corporation of
New York

Application November 3, 1939, Serial No. 302,746

7 Claims. (Cl. 138—30)

The present invention relates to variable capacity reservoirs for use in supplying oil or other insulating liquid to or receiving it from cable systems and parts thereof as the volume of the liquid changes with temperature changes. As examples, such reservoirs may be utilized to supply liquid insulation to terminals connected to conductors of cable systems and to the casings enclosing the joints which unite adjacent ends of insulated electric conductors. The cables may be of the so-called solid type or of the fluid filled type. The general purpose of these reservoirs is to ensure the complete filling of the parts of the cable system, however it is constructed, with sufficient liquid insulation to prevent the formation of objectionable voids within the cable sheaths and other parts forming the enclosure of the insulated conductors.

The present invention is in the nature of an improvement over the construction set forth in the patent to Eby 1,823,731, issued September 15, 1931, and has for its object the provision of a reservoir which is less costly in construction than those heretofore employed to the end that their wider use may be economically justified. In this connection, it may be pointed out that such reservoirs on account of the care which must be exercised in their manufacture are relatively expensive. By decreasing their manufacturing cost, it follows that their use will be justified in installations where otherwise such would not be the case.

A further object of the invention is the provision of an improved type of reservoir which is applicable for cable systems operating on somewhat different principles. For example, they may be used in cable systems requiring gravity feed reservoirs, those requiring pressure reservoirs and those requiring the use of gas in the reservoirs adjusted to different pressures to compensate for different elevation of parts of the cable, as in the so-called balance pressure cable systems.

For a consideration of what I believe to be novel and my invention, attention is directed to the accompanying description and the claims appended thereto.

In the accompanying drawing which is illustrative of my invention, Fig. 1 is a view in side elevation of a reservoir with certain parts broken away to illustrate the interior construction; Fig. 2 is an enlarged view, chiefly in section, of a part of one of the reservoir cells; Fig. 3 is a view showing the application of a gas filled tank to a reservoir by which a greater amount of gas

is made available to suit the service requirements; and Fig. 4 is a detail sectional view of the breather for the reservoir.

The tank or casing of the reservoir comprises two truly cylindrical parts 4 and 5 which may be made of thin gauge steel or equivalent material. The purpose in using thin material is to reduce weight and cost. The reservoirs are commonly supported from the roofs of manholes and on that account all reductions in weight which can be made in the tank and contained parts are highly desirable. Manholes are usually relatively small and crowded so that reduction of weight of the reservoirs is one of the many considerations. The halves of the casing are made separately and for a short distance near the center of the tank, considered as a whole, are in telescopic relation as indicated at 6. The joint is subsequently brazed or soldered so the tank will be pressure tight. 7 and 8 indicate straps by which the tank can be suspended from the ceiling of the manhole or other containing structure. The halves of the tank are each truly cylindrical as distinguished from the tank of the said Eby patent which has a longitudinal enlargement or bulge to receive a manifold, as shown in Fig. 5 thereof. By doing away with a manifold, the parts become simpler to construct and also less expensive because less metal is employed. The elimination of the manifold does away with the projection or bulge in the wall of the tank which accommodates it. This results in a simpler and cheaper tank and also simplifies the manufacturing operation of uniting and soldering the halves of the tank at the center. The actual inside diameter of the tank for the same class of service is or may be the same as that of prior types but the elimination of the bulge will reduce the overall dimension by about two inches. The more important feature is, of course, the reduction in the cost of manufacture. The reason why no manifold is required will appear later on.

Within the tank or casing is a relatively large number of similar cells 9 made of disks of thin sheet metal, the central portion of each side wall being corrugated to increase the flexibility. The peripheral flanges or edges 10 of each pair of disks forming a cell are suitably united as by electric welding, for example. The cells are placed side by side in the tank to form a group. Where the interior of the cells is open to the atmosphere, as is the case of gravity feed reservoirs, the metal used in their manufacture should be non-corrosive whereas for the other types

common steel may be used. In respect to the features just above mentioned, the arrangement shown in Fig. 6 of the Eby patent may be followed. However, there is this important difference. In the patented structure there is no means whatsoever to enable the gas pressure within the cells to be adjusted whereas there is such a means in the present structure. This is of particular importance in balanced pressure cable systems because the pressure in the cells of one reservoir can thus be readily adjusted with respect to those of another reservoir to take care of differences in the profile of the cable, by the admission of more or less gas under determined pressure. The gas employed may be air but desirably is of a kind such as CO₂, for example, that does not in the case of a leaking cell seriously affect the cable oil or other liquid which before use is carefully degassed. The cells of the reservoir are submerged in the oil or other liquid from the cable. Where a manifold is used, the cells are connected thereto in parallel and, because of the viscosity of the liquid, the manifold and the pipes connecting the cells and manifold have to be of substantial cross-sectional area to reduce the resistance to flow. Because no manifold is employed with cells connected thereto in parallel, a further departure from the patented structure is made in that the cells are connected in series relation one to the other. Because the cells are filled with gas which moves freely, as distinguished from a liquid which moves more slowly, the tubes connecting the cells in series relation may be made of much smaller cross section than where liquid is employed. The gas pressure within the cells may be that of atmospheric air for the gravity feed type of reservoirs, and at an elevated pressure for the pressure type reservoirs and also for the balanced pressure type.

In Fig. 2 is shown on an enlarged scale a portion of one of the cells, which cells are all similar in construction. 11 and 12 indicate the corrugated side walls or disks of a cell, and 13 the portions thereof which extend toward each other, the high parts of the corrugations as well as the low parts being respectively in axial register so as to be self supporting under certain pressure conditions. Each of the side walls is provided with a flattened inset or depressed portion 14 which has an opening to receive a thimble or ferrule 15, the latter having a bore in which an end of the connecting tube or conduit 16 is snugly fitted, after which the parts are united and sealed as, for example, by soldering, brazing or welding. The thimbles are seated and sealed in the walls of the cells prior to the operation of uniting the flanges of the walls. The thimbles desirably have enlarged heads so as to ensure a good joint between them and the thin walls. The heads are desirably located inside of the cell to facilitate the assembly operation, but may be located outside if desired. The flattened or inset portions 14 of the two side walls are angularly displaced to permit of the use of reasonably long and relatively flexible tubes or conduits 16 so as to prevent injury thereto caused by vibration, improper handling of the group of cells, etc. The tubes are desirably bent to conform generally to an angular portion of each cell. By connecting the ends of the tubes, one to one cell wall and the other to the wall of an adjacent cell, all of the cells of a group are connected in series relation. It will be noted that the peripheral portions or flanges of the side walls extend radially well be-

yond the tubes 16 and thus protect them from injury, particularly during manufacture. Due to this arrangement, the cells when assembled into a group can be handled as a unit without injury to the tubes.

It will be noted that each tube 16 is connected at one end to the left-hand side wall of one cell and at the opposite end to the right-hand wall of the adjacent cell. This has the advantage that 10 the tubes do not have to cross over the flanges 10 where they would be liable to injury, and also the tubes may be made shorter for the same 15 angular spacing of the insets 14. Due to the protection afforded by the flanges 10 which have a substantially greater diameter than that of the 20 region of the side walls containing the insets, the tubes may be of light section and hence more easily bent to the desired shape. The use of thimbles facilitates the making of the connections between cells, as will be seen from inspection.

Where it is desired to have the cells operate at atmospheric pressure, as in a gravity feed reservoir, the outermost cell is connected by 25 means of a relatively long tube or conduit 17 to a breather 19 which maintains the chambers of the cells at atmospheric pressure. The breather 19 is designed so as to prevent foreign matter or free water from entering the chambers of the 30 cells. Atmospheric air flows into and out of the breather through holes 19^a, Fig. 4, in the base and then up through a mass of glass wool 19^b or other equivalent material and then down through the central tube 19^c into the cells. Thus foreign 35 matter or free water entering through the holes in the base is trapped in the mass of glass wool and prevented from entering the central tube leading to the cells. With the chambers of the 40 cells directly exposed to the effects of atmospheric air, the walls thereof will move toward and away from each other to a limited extent with changes in temperature; thus such changes will be automatically compensated for. Because the walls are directly exposed to atmospheric air, they will 45 respond to changes thereof more quickly than would be the case if the action was indirect as through a body of liquid.

Where it is desired to have the cells operate on a balanced pressure system, an outermost cell 50 is connected by means of a relatively long tube or conduit 31, Fig. 3, to an automatically closing gas valve 41, such as may be used for automobile inner tubes or other purposes. By changing the 55 pressure of the gas within the group of cells, as by admitting gas at the desired pressure or by opening the valve and permitting gas to escape, the force exerted by the walls of the cell on the liquid in the tank may be changed or adjusted at will.

The cells are secured in a holder which 60 comprises a pair of heads 21, Fig. 1, of which one is shown, the heads being held in adjusted position by a suitable number of angularly spaced clamps or members 22, the ends of which are turned over to engage the heads. This arrangement holds the cells in proper contact relation and is 65 also desirable in that it permits of handling a number of cells as a unit.

The bottom of the tank is provided with a removable plug 26 to permit draining thereof whenever 70 it is so desired. On one of the heads of the tank is a fitting 27 through which the liquid in the tank is permitted to flow into and out of the cable, terminal or other device connected thereto. 75 The fitting is also provided with a shut-off valve

and a filling port 28 through which oil may be added to the reservoir and the pressure thereof measured by means of a gauge. The opening in the fitting through which the liquid flows to and from the cable is of substantial size so that the resistance to flow is small, smaller in fact than the resistance to flow due to the use of a manifold and the tubes connecting the cells in parallel thereto as has been the practice heretofore.

In Fig. 3 is illustrated an arrangement which is more especially intended for a balance pressure reservoir in which it is desirable to have a greater gas space. This is provided for by having an auxiliary chambered tank 29, one end of which is telescoped over one end of the main tank containing the cells in the same manner as the two halves of the main tank are arranged, and in like manner the tanks are soldered or otherwise united in a gas-tight manner. It is necessary where an auxiliary tank is used to connect it with the cells in the main tank. The connection may be external to the tanks or internal. The external arrangement will first be described. The left-hand head of the main tank has a boss 30 secured thereto, and a tube 31 permits introduction or withdrawal of gas from the cells. Its function is similar to tube 17 of Fig. 1, the difference being that the gas passing therethrough is under positive pressure. The periphery of the boss is screw-threaded, and seated thereon is a tubular member 32 having an internal screw thread. The member has a central bore, and opening into it is a lateral passage the outer end of which is screw-threaded to receive the elbow 33. To the auxiliary tank 29 is secured an elbow 34, and the two elbows are connected by a tube 35, the connection between the tube ends and the elbows being accomplished by detachable compression fittings 36. The exposed head of the main tank is also provided with a fitting 42 having the functions of parts 27 and 28 of Fig. 1.

The internal arrangement will now be described. The right-hand head of the main tank is provided with a boss 25 which is welded or otherwise secured thereto. Extending through the boss and sealed therein is a tube 25^a, one end of which opens into the chamber of the auxiliary tank 29 and the other end into the chamber of a cell, the connection between the tube and the cell being similar to that shown in Fig. 2. This construction has the advantage that all of the tubes are within the tanks and hence are fully protected by the walls thereof from injury. The external arrangement, on the other hand, has the advantage that the parts are accessible from the outside of the tank. For most installations the internal arrangement is the more desirable. Should occasion arise, both internal and external arrangements may be employed.

Due to the auxiliary tank, a large volume of gas under determined pressure is constantly available for supplying the cells of the main reservoir with gas, the cells as before compressing when the liquid pressure of the main reservoir or tank rises and expanding when the pressure drops. This arrangement thus ensures a proper pressure on the liquid in the cable, terminal or other device to which the reservoir is connected, and is particularly useful in obtaining full displacement of the walls of the cells at the lowest cable pressure. The member 32 has a shoulder and a part of reduced cross section, the said part being externally screw-threaded to receive a sealing cap 37. Between the cap and shoulder is a packing 38 to seal the joint. The member has

5 a screw-threaded plug 39 through which gas under pressure may be admitted to or removed from the cells through the tube 31. The plug has a suitable valve 41 such as may be used on automobile inner tubes which opens to admit gas under pressure superior to that in the cells and automatically closes when the connected supply pipe is removed from the outer end of the valve. Oil or other liquid is admitted to the tank 10 through a fitting 42 which is similar to parts 27 and 28 of Fig. 1.

15 For the purposes of illustration, the fittings in Fig. 3 have been greatly enlarged with respect to the tank so that the interior parts may be shown. 15 In practice, they bear substantially the relation to the tanks as shown in Fig. 1.

From what has been said it will be noted that when the reservoir is used as a gravity feed device the tank will be completely filled with oil as contrasted to a filling composed of atmospheric air and a limited amount of immersion oil as in the prior design as exemplified by the Eby structure. This arrangement decreases the opportunity for rust to form. It also results in a reduction of cost since all the parts except the cells may be made of common steel instead of non-corrosive material. The fact that the tank is filled with oil means that the inside wall thereof need not be galvanized with the result of a saving in cost.

30 It is further to be noted that in the improved construction herein set forth the tank, when used as a balance pressure reservoir, is filled with oil under positive pressure and the cells with gas, 35 whereas in the prior construction, used for many years, the tank was filled with gas and the cells with oil. This change or reversal, while it may on first consideration appear relatively simple, is nevertheless of material importance. One of the major difficulties with the old type of reservoir is the amount of time required to locate minute gas leaks which sometimes occur in service. There have been cases where several weeks have been spent by the operators of public utilities in 40 trying to locate minute gas leaks in the old type reservoirs without success and finally the reservoirs had to be removed from the connected cable and manhole before repairs could be made. In this connection it should be borne in mind that repairs on high tension cable systems can be 45 made with safety only when the cable is out of service. Obviously a utility is not in a position to shut down at will important cables in its system on account of interruption of service to customers. Furthermore, because the oil used in the cable is highly degasified, the job of removing one reservoir and substituting another is not as simple as it would first appear. It requires care to prevent the entrance of foreign matter 50 into the cable and evacuation of the connecting pipes and other parts, and may even require a vacuum treatment of the cable ends terminating in the joint casing where the reservoir connections are made. All operations involving the 55 opening of a cable have to be performed with the utmost care. With my improved construction, where the tank is completely filled with oil under determined pressure, minute leaks, should they appear, are relatively easy to locate because the oil smudges the outside of the tank at the place of leakage which would not be the case if the tank were filled with gas.

70 What I claim as new and desired to secure by Letters Patent of the United States, is:

75 1. A variable capacity reservoir comprising a

sealed tank adapted to contain a body of liquid, conduit means through which the liquid flows between the tank and the apparatus served thereby, a plurality of individual sealed chambered cells having side walls movable toward and away from each other as the volume of the liquid changes, the cells being located within the tank and submerged in its contained liquid, in combination with conduits connecting the cells one to another in series relation, and a conduit for admitting gas under determined pressure to one of the cells and through it to the others, one end of the conduit being accessible from outside of the tank.

2. A variable capacity reservoir comprising a main sealed tank containing a body of liquid, conduit means through which the liquid flows between the tank and the apparatus served thereby, a plurality of chambered cells submerged in the body of liquid, in combination with conduit means connecting the chambers of the cells in series relation, a conduit means accessible from outside of the tank for supplying gas under determined positive pressure to one of the cell chambers, an auxiliary tank having the open end thereof in telescopic relation with the wall of the main tank containing a relatively large body of gas under the same pressure as that in the cell chambers, and a conduit connecting one of the cell chambers with the interior of the auxiliary tank and through which gas is supplied to the other cells.

3. A variable capacity reservoir comprising a tank adapted to contain liquid, a group of chambered cells submerged therein, each cell having flexible disk-shaped side walls united at their peripheral edges, each wall having an inset portion, conduits entering the walls of the cells through the insets, each conduit extending from the inset of one cell wall to a similar inset in the wall of the cell immediately adjacent thereto to connect them in series relation, and means for admitting fluid to one of the cells under a determined pressure.

4. A variable capacity reservoir comprising a tank containing liquid, a group of chambered cells submerged therein, each cell having a pair of right and left-hand disk-shaped side walls, the peripheral edges of the disks being united to form chambers, each side wall having an inset therein, a thimble mounted in each of the in-

sets, a tube connecting the thimble of a right-hand disk with the thimble of a left-hand disk to connect the chambers of the cells in series relation, and means for admitting elastic fluid under determined pressure to one of the chambers for supplying the others.

5. A variable capacity reservoir comprising a tank containing a body of liquid, a group of cells submerged in the body, each cell having a pair of disk-shaped flexible side walls which between them define a chamber and have peripheral flanges, each side wall having an opening, the openings in each cell being in angularly spaced relation to increase the distance between the opening in adjacent walls, a tube located between the flanges of each pair of adjacent cells for conveying fluid from an opening in one cell to an angularly displaced opening in an immediately adjacent cell, and means for admitting fluid under determined pressure to one of the group of cells, the tubes connecting the chambers of the cells in series so that all are subjected to the effects of the fluid.

6. A variable capacity reservoir comprising a tank, a plurality of expansible and contractible chambered cells located therein, individual conduits arranged to connect the chambers of the cells in series relation, a filling of gas for the chambers and conduits, tubular means connected to one of the cells through which fluid may be introduced into the chambers of all of the cells or withdrawn therefrom, and a filling of liquid for the tank which completely surrounds the chambered cells.

7. A variable capacity reservoir comprising a tank containing liquid, a group of gas filled chambered cells arranged side by side and submerged in the liquid, each cell comprising a pair of flexible disk-shaped side walls having flanges of larger diameter than the walls for uniting them, conduits opening into the chambers of the cells for connecting them in series relation, the conduits being located in the spaces between adjacent pairs of flanges and protected thereby, each conduit being connected at one end to a side wall of one cell and at the other end to the adjacent side wall of another cell, the points of connection to the walls being angularly displaced, and conduit means admitting gas to one of the cell chambers.

THOMAS C. AITCHISON.
